(57) **CLAIM**

The ornamental design for a flexible catheter with guide wire, as shown and described.

DESCRIPTION

FIG. 1 is a perspective view of a flexible catheter with guide wire, showing our new design;

FIG. 2 is a top view thereof, the bottom, left side and right side views being a mirror image to the top view;

FIG. 3 is an enlarged rear view thereof;

FIG. 4 is an enlarged front view thereof; and,

FIG. 5 is an enlarged partial cross-section view of the area labeled 5 in FIG. 2, along the line labeled 5-5 of FIG. 4. The dashed broken lines illustrate portions of the flexible catheter with guide wire that form no part of the claimed design. The dash-dot-dash broken lines in FIGS. 2 and 5 define the boundary of the partial cross-section view and form no part thereof. The diameters of the inner and outer members shown in FIG. 5 remain constant along the lengths of the inner and outer members.
